B. BOWLER.
ARTIFICIAL HAND.

APPLICATION FILED DEC. 18, 1917, RENEWED FEB. 18, 1919.

1,299,543.

Patented Apr. 8, 1919.

UNITED STATES PATENT OFFICE.

BARTHOLOMEW BOWLER, OF TORONTO, ONTARIO, CANADA.

ARTIFICIAL HAND.

1,299,543.

Specification of Letters Patent.

Patented Apr. 8, 1919.

Application filed December 18, 1917, Serial No. 207,712. Renewed February 18, 1919. Serial No. 277,818.

To all whom it may concern:

Be it known that I, BARTHOLOMEW BOWLER, of the city of Toronto, in the county of York, Province of Ontario, Canada, have invented certain new and useful Improvements in Artificial Hands, of which the following is a specification.

This invention relates to substitutes for the human hand in which utility rather than appearance is considered and my object is to devise a hand by means of which various tools or utensils may be resiliently and therefore securely grasped, and which may be rotarily adjusted on an axis longitudinal of the arm and also rotarily adjusted on an axis at right angles to the aforesaid axis.

I attain my object by means of the constructions hereinafter described and illustrated in the accompanying drawings in which—

Figure 1 is an elevation of my improved hand connected to an artificial arm member;

Fig. 2 a similar view partly in section taken at right angles to Fig. 1;

Fig. 3 a longitudinal section of the connections between the hand member and the arm member; and

Fig. 4 a section on the line *a—b* in Fig. 3.

In the drawings like numerals of reference indicate corresponding parts in the different figures.

1 is an artificial arm member of ordinary construction adapted to be laced to a stump. The end of the arm member is formed by a flat metal plate 2 to which the hand member is connected. The hand member is provided for the purpose with a hollow boss 3 internally threaded. Into the boss is screwed a disk 4 through which is formed a keyhole slot 5, through which may be passed the key headed pin 6 secured to the artificial arm member and projecting from the center of the plate 2. The hand member may thus be easily engaged with or disengaged from the arm member and a rotary adjustment on an axis longitudinal of the arm also obtained.

50 To clamp the hand member in any position to which it is rotated, it is merely necessary to rotate the disk 4, which, by engaging the head of the pin 6, jams the rim of the hollow boss against the plate 2. Preferably a fiber washer 7 is interposed between the parts to give a better frictional grip.

The disk is rotated by means of the pin 8, which is secured to the rim of the disk 4 and projects through a slot 9 formed in the wall of the hollow boss. The slot is provided with a series of enlargements 10 into any one of which fits the sleeve 11 slidable on the pin 8. The sleeve is normally pressed toward the slot by a coil spring 12, which engages the head of the pin and an internal shoulder on the sleeve. The sleeve will thus, by engaging the enlargements 10, hold the pin in any position to which it may be moved.

The boss 3 is provided with the jaws 13 between which is pivoted the shank 14 of the hook 15. The hook is thus adapted to swing on an axis at right angles to an axis longitudinal of the arm on which the boss 3 turns.

It will also be noted that the axis on which the shank is pivoted lies substantially in the same plane as the hook.

The pivot 16 of the shank passes through one jaw 13, and the shank, and is threaded 80 into the other jaw. A headed pin 17 passes through an axial hole in the pivot and has a disk 18 secured to the end remote from the head. The disk has a projection 19 formed thereon which extends through a 85 hole in the adjacent jaw and is adapted to enter any one of a series of holes 20 formed in the shank. The pin is normally yieldingly pressed to an engaging position by a coil spring 24 engaging shoulders formed 90 on the pin and the pivot respectively. By pushing on the pin, the projection may be disengaged and after the shank has been moved to bring another hole therein under the projection, the latter will automatically 95 engage it. Preferably the pivot is tapered so that it may be adjusted for wear, a slot 25 being provided in its outer end for engagement with a suitable tool by means of which it may be turned.

The hook is double and the parts of each half remote from the shank are substantially arc-shaped as shown, the center from which the arc is struck being located in the shank preferably near the outer end thereof. Between the halves of the hook is pivoted a clamp arm 21, which is preferably formed of resilient material and is curved in the direction of its length as shown. Means are provided for adjustably connecting the 110 clamp arm and the arc-shaped parts of the hook. I preferably employ a dog 22 piv-

oted on the clamp arm and normally pressed by a spring 23 to engage the teeth of a rack, preferably a ratchet rack, formed on the outer end of the arc-shaped part of each half 5 of the hook. The arm is thus easily swung to press against the outer side of any object with which the hook may be engaged, and as the arm is resilient a close tight grip is easily obtained on the object. The resiliency of 10 the arm is thus of importance, as it is impossible to make any ordinary adjustment which would exactly fit the various sized objects which the hook may be required to grasp. With the ratchet rack the adjustment is very 15 quickly obtained and any desired pressure may be brought against the object owing to the resiliency of the clamp arm.

Preferably the inner part of the hook is 20 polygonal rather than circular in form so as to insure gripping a round object at a plurality of points on its periphery.

As the hand member is rotarily adjustable on the arm member and may also be 25 swung to any desired position to one side of the other of the axis of the arm member, practically any necessary position of the hook can be obtained, which adapts it for use in grasping a variety of tools and for performing a great variety of operations.

30 What I claim as my invention is:—

1. In an artificial hand, a shank; a hook formed thereon having the part thereof remote from the shank substantially arc-shaped; a clamp arm pivoted on said hook substantially at the center from which the aforesaid arc is struck; and adjustable connecting means between the clamp arm and the arc-shaped part of said hook.

2. In an artificial hand, a shank; a hook 40 formed thereon having the part thereof remote from the shank substantially arc-shaped; a curved, resilient clamp arm pivoted on said hook substantially at the center from which the aforesaid arc is struck; and 45 adjustable connecting means between the clamp arm and the arc-shaped part of the said hook.

3. In an artificial hand, a shank; a hook formed thereon having the part thereof remote from the shank substantially arc-shaped and having a rack formed thereon; a 50 clamp arm pivoted on said hook substan-

tially at the center from which the aforesaid arc is struck; and a spring actuated dog carried by the clamp arm and adapted to engage the rack. 55

4. An artificial arm member provided at its end with a flat plate and a key-headed pin projecting from the plate, in combination with a hand member provided with a hollow 60 interiorly threaded boss with a slot at one side extending through its wall; a disk screwed into the boss provided with a key-hole slot whereby the pin may be engaged with said disk; and a pin projecting through 65 the aforesaid slot and connected with the disk whereby the latter may be rotated to jam the edges of the boss against the plate aforesaid.

5. An artificial arm member provided at 70 its end with a flat plate and a key-headed pin projecting from the plate, in combination with a hand member provided with a hollow interiorly threaded boss with a slot at one side extending through its wall and 75 provided with a series of enlargements along its length; a disk screwed into the boss provided with a key-hole slot whereby the pin may be engaged with said disk; a pin projecting through the aforesaid slot and connected with the disk whereby the latter may be rotated to jam the edges of the boss 80 against the plate aforesaid; and a spring actuated sleeve carried by the pin adapted to engage the enlargements of said slot to hold 85 the pin in any position to which it may be moved.

6. The combination of a hand provided with a boss for attachment to an artificial arm member; jaws formed on said boss; a 90 hook member having a shank fitted between said jaws; a hollow pivot pin passing through one jaw, through the shank and threaded into the other jaw; a pin passing through said hollow pivot; a disk on the end 95 of the pin provided with an inwardly directed projection, the adjacent jaw being provided with a hole through which the projection passes and the shank with a series of holes with any one of which the projection 100 may engage.

Signed at Toronto, Canada, this 5th day of December, 1917.

BARTHOLOMEW BOWLER.
